UNITED STATES PATENT OFFICE

155,502

DESIGN FOR AN ELECTRIC PLUG CONNECTOR

Wayne T. Gossard, Los Angeles, Calif.

Application June 3, 1949, Serial No. 3,034

Term of patent 14 years

(Cl. D26—1)

To all whom it may concern:

Be it known that I, Wayne T. Gossard, a citizen of the United States and resident of the city of Los Angeles, county of Los Angeles, State of California, have invented a new, original, and ornamental Design for an Electric Plug Connector, of which the following is a specification, reference being had to the accompanying drawing, forming a part thereof, in which:

Fig. 1 is a front view of an electric plug connector, showing my new design;

Fig. 2 is a side view;

Fig. 3 is a top view;

Fig. 4 is a bottom view; and

Fig. 5 is a rear view thereof.

I claim:

The ornamental design for an electric plug connector, substantially as shown.

WAYNE T. GOSSARD.
